UNITED STATES PATENT OFFICE.

FRANK B. HENNEY, OF YUCAIPA, CALIFORNIA.

CRATE-SALVAGING APPARATUS.

Application filed February 16, 1925. Serial No. 9,553.

My invention relates to a crate salvaging apparatus, more particularly adapted for salvaging fruit boxes, such as apple boxes.

The manufacturing and using new apple or other fruit boxes is very expensive, and since a great many used boxes, with contents sold and emptied, are available, I am using these latter boxes for packing an inferior grade of fruit. These boxes, however, carry foreign labels and various other markings incidental to going through the trade, and, therefore, are not always desirable to be used in this condition. The machine or apparatus which I have invented, is adapted to take the boxes apart with very little expense and salvage practically all of the shook, that is, the ends, sides, bottom, top and cleats of the box, the portion of the apparatus for removing the bottoms of the boxes are not shown or described.

The objects of my invention are; First, to provide an apparatus of the class mentioned for removing the sides of a box or crate; second, to provide an apparatus of this class for simultaneously removing the opposite long sides of the box from the end members thereof; third, to provide an apparatus of this class having a foot lever means whereby the box adapted to be disassembled or salvaged is clamped in an inverted position at the top portion of the apparatus and whereby the relatively thin long box members secured at their ends to the end members are forced or pried from said end members; fourth, to provide novel foot lever means for performing the functions above mentioned; fifth, to provide novel means for removing the nails from the box members pried from said end members; sixth, to provide a novelly constructed box salvaging apparatus, and seventh, to provide an apparatus of this class which is simple and economical of construction, durable, efficient, easy to operate, and which will not readily deteriorate or get out of order.

With these and other objects in view, as will appear hereinafter, my invention consists of certain novel features of construc-

tion, combination and arrangement of parts and portions, as will be hereinafter described in detail and particularly set forth in the appended claims, reference being had to the accompanying drawings and to the characters of reference thereon, which form a part of this application, in which:

Figure 1 is a front elevational view of my box salvaging apparatus; Fig. 2 is a sectional elevational view thereof, with the section taken through 2—2 of Fig. 3 on a reduced scale; Fig. 3 is a fragmentary plan view of my apparatus on an enlarged scale; Fig. 4 is a fragmentary sectional elevational view of the upper portion of my apparatus, with the section taken through 4—4 of Fig. 3, and Fig. 5 is a perspective view of the nail removing means of my apparatus.

Like characters of reference refer to similar parts and portions throughout the several views of the drawings.

The frame 1, upright supports 2, clamping levers 3, brackets 4, links 5 and 6, foot lever 7, brackets 8, spring 9, rod 10, prying members 11, bolts 12, lever arms 13, shaft 14, journals 15, journal blocks 16, shaft rotating arm 17, link 18, bracket 19, foot lever 20, spring 21, retaining members 22, nail removing plate 23, and the angular guide member 24, constitute the principal parts and portions of my apparatus.

The frame 1 of my apparatus may be of any construction desired, but is preferably provided at its sides with supporting tables 1^a. At the middle portion of the frame are secured a pair of upright supporting members 2, which are positioned in spaced relation with each other, the distance between their outer sides at their lower ends being substantially the length of the inside of the boxes adapted to be taken apart. These members 2 are preferably inclined toward each other at their upper ends so as to permit the boxes, indicated by B, to be readily positioned over said members. The upright supporting members 2 are provided at their upper ends with upwardly extending lugs 2^a which are adapted to extend

through the space or longitudinal slot usually provided between the separate members S^1 of the bottom of the box. These lugs 2^a are adapted to position the upper end of the box laterally relatively to the frame of the machine.

The upright supporting members 2 are supported relatively to each other at their upper ends by means of a connecting rod 10.

10 In the top 1^b of the frame 1 are provided slots 1^c at the outer sides of the members 2, through which slots extend the upper or clamping ends of the clamping levers 3 which are pivotally mounted intermediate 15 their ends on brackets 4 secured underneath the top of the frame. The other or lower ends of the levers 3 are pivotally connected to the one end of links 5, which links are pivotally connected at their opposite ends with each other. At the pivotal connection of the links 5 is pivotally connected another link 6 which, in turn is pivotally connected at its opposite end intermediate the ends of the foot lever 7, which foot lever is pivotally connected at its rear end to a bracket 8 mounted on the frame 1. At the pivotal connection of the links 5 with each other is connected the one end of a tension spring 9 which is secured at its opposite end to the under side of the top of the frame. When the foot lever 7 is depressed, the ends of the links 5 connected with each other are lowered, forcing the lower ends of the clamping levers 3 apart and their upper ends toward each other, clamping the box positioned over the members 2 in position on the top of the table and against the members 2. On the top 1^b of the frame 1 and between the upright supporting members 2 are secured a 20 pair of spaced apart blocks 16 on which are mounted journal members 15 in which is revolvably mounted a shaft 14. Near the ends of the shaft 14 are secured pairs of oppositely disposed slotted lever arms 13 which are pivotally connected by means of bolts 12 to inwardly extending arms 11^a of the upright prying members 11, a pair of which is positioned near the ends of the shaft 14. The inwardly extending arms 11^a of each 25 pair of prying members 11 extend toward the oppositely positioned prying member and on the opposite sides of the shaft 14. Each of the inwardly extending arms 11^a is preferably provided with horizontal slots 11^b through which extend inwardly bent lugs 2^b secured to the inner sides of the upright supporting members 2, as shown best in Figs. 3 and 4. The lugs 2^b are adapted to guide the prying members 11 in their horizontal reciprocal movement and retain the outer prying portions thereof in a substantially upright position.

The shaft 14 is provided intermediate its ends with an outwardly extending arm 17 which is pivotally connected at its outer end,

by means of a link 18, with a bracket 19 secured intermediate the ends of the foot lever 20. The foot lever 20 is pivotally mounted at its rear end on upwardly extending brackets 1^d secured on a cross member at the 70 lower portion of the frame 1, as shown best in Figs. 1 and 2. To the bracket 19 is connected the one end of a tension spring 21 which is connected at its opposite or upper end to the under side of the top of the frame 75 for retaining the foot lever 20 in its upper position.

On both sides of the middle portion of the apparatus are provided pairs of spaced apart upwardly and outwardly inclined box member supporting brackets or retaining members 22, which are secured at their lower ends to the top of the frame, as shown best in Figs. 3 and 4, for holding the side members S of the box in position after the same are pried from the end members E of the box, as shown by dotted lines in Fig. 4.

When the box, desired to be taken apart, is positioned over the upright supporting members 2 and clamped in position by the clamping levers 3, as described above, by means of the foot lever 7, the other foot lever 20 is depressed, which rotates the shaft 14 in a clockwise direction, forcing the prying members 11 outwardly against the inner sides of the lateral side members of the box B , prying said members from the end members of the box. If desired, the side edges of the end members E of the box may be similarly clamped between the upright supporting members 2 and the clamping levers 3, and the bottom panels or members S^1 pried from the end members in a similar manner.

The means for removing the nails from the ends of the box members which members were secured to the end members of the box consists of a plate 23, shown best in Fig. 5, secured to the front portion of the upper side of the top of the frame, and an angular guide 24 secured to the under side of the front portion of the plate 23. Said plate is provided with a slot 23^a near its front edge of a width to receive the shank portions of the nails of the box but sufficiently small to retain the heads of the nails N at the upper side of the plate, as shown best in Fig. 5. When desiring to remove the nails from the members of the box, said members are struck with the ends provided with the nails against the plate 23 with the points of the nails projecting downwardly. The impact of said members against the plate 23 drives the nails outwardly. The nails are then inserted into the slotted portion 23^a of the plate 23 with the top side of the box members against the under side of the inclined member 24 and moved to the left. The latter movement of the boards or box members provided with the nails removes said nails completely from 105 110 115 120 125 130

the box members. At the inner end of the slot 23^a of the plate 23 is provided an enlarged hole 23^b through which the nails are permitted to drop into any receptacle not shown, after being removed from the box members.

Though I have shown and described a particular construction, combination and arrangement of parts and portions, I do not 10 wish to be limited to this particular construction, combination and arrangement, but desire to include in the scope of my invention the construction, combination and arrangement substantially as set forth in 15 the appended claims.

Having thus described my invention, what I claim as new and desire to secure by Letters Patent is:

1. In a crate salvaging apparatus, a 20 frame, upright positioning members secured on said frame, prying members reciprocally mounted to press outwardly at the upper portion of said frame between said upright positioning members, and foot lever means 25 for clamping a box over said positioning members and for actuating said prying members.

2. In a crate salvaging apparatus, a 30 frame, upright positioning members secured on said frame, clamping members shiftably mounted at the outer sides of said positioning members, lever means for actuating said clamping members, a plurality of prying members reciprocally mounted to press outwardly at the upper portion of said frame 35 between said positioning members, and another lever means for actuating said prying members.

3. In an apparatus of the class described, 40 a frame, upright positioning members mounted on said frame, clamping members shiftably mounted at the outer sides of said positioning members, lever means for actuating said clamping members, a plurality of prying members reciprocally mounted at the upper portion of said frame between 45 said positioning members, a shaft rotatably mounted on said frame between said positioning members, arms connecting said shaft with said prying members, and a foot lever connected with said shaft for rotating the same.

4. In a crate salvaging apparatus, a 55 frame, a plurality of permanent upright positioning members provided at their upper ends with positioning lugs adapted to be inserted through slotted portions in the walls of boxes adapted to be taken apart, clamping members positioned at the outer sides of said upright positioning members, and foot lever means for actuating said clamping members whereby the ends of boxes adapted to be positioned over said positioning member may be clamped in position.

5. In a crate salvaging apparatus, a frame, a plurality of permanent upright positioning members provided at their upper ends with positioning lugs adapted to be inserted through slotted portions in the 70 walls of boxes adapted to be taken apart, clamping levers pivotally mounted intermediate their ends at the outer sides of said upright positioning members adapted to clamp ends of boxes between the same and 75 said upright positioning members, links connected at their one ends to the lower ends of said clamping levers and at their opposite ends with each other, and a foot lever means pivotally connected with the 80 ends of said links connected with each other.

6. In an apparatus of the class described, a frame, a plurality of upright positioning members provided at their upper ends with 85 positioning lugs adapted to be inserted through slotted portions in the walls of boxes adapted to be taken apart, clamping members positioned at the outer sides of said upright positioning members, foot lever means for actuating said clamping members 90 whereby the ends of boxes adapted to be positioned over said positioning members may be clamped in position, prying members reciprocally mounted at the upper portion of said frame adapted to engage the inner sides of the box members connecting said end members, and means for reciprocating said prying members.

7. In an apparatus of the class described, a frame, a plurality of upright positioning members provided at their upper ends with 100 positioning lugs adapted to be inserted through slotted portions in the walls of boxes adapted to be taken apart, clamping members positioned at the outer sides of said upright positioning members, foot lever means for actuating said clamping members 105 whereby the ends of boxes adapted to be positioned over said positioning members may be clamped in position, prying members reciprocally mounted at the upper portion of said frame adapted to engage the inner sides of the box members connecting said end members, a shaft rotatably 110 mounted on said frame between said positioning members, arms connecting said shaft with said prying members, and a foot lever connected with said shaft for rotating the same.

8. In a crate salvaging apparatus, a frame, a clamping means in connection with the upper portion thereof, pairs of oppositely disposed outwardly pressing prying members positioned between said 115 clamping means and reciprocally mounted relatively to said frame, and means for actuating said prying members in opposite directions, for removing side members from crates.

9. In an apparatus of the class described, a frame, a clamping means in connection with the upper portion thereof, pairs of oppositely disposed prying members positioned between said clamping means and reciprocally mounted relatively to said frame, a shaft rotatably mounted between said prying members, operating arms secured to the

ends of said shaft and pivotally connected with said prying members, and lever 10 means for rotating said shaft.

In testimony whereof, I have hereunto set my hand at Los Angeles, California, this 3rd day of February, 1925.

FRANK B. HENNEY.
